A. L. FOSTER

DEVICE FOR ADJUSTABLY CONTROLLING THE LOCATION
OF ROLLER SHAFTS IN PAPER FEEDING MACHINES

Filed May 5, 1927

FIG. I.

FIG. II.

INVENTOR:

ARTHUR L. FOSTER,
by *Arthur E. Raigh,*
Attorney.

UNITED STATES PATENT OFFICE.

ARTHUR L. FOSTER, OF MIDDLETOWN, NEW JERSEY, ASSIGNOR TO MANIFOLD SUPPLIES COMPANY, OF BROOKLYN, NEW YORK, A CORPORATION OF NEW YORK.

DEVICE FOR ADJUSTABLY CONTROLLING THE LOCATION OF ROLLER SHAFTS IN PAPER-FEEDING MACHINES.

Application filed May 5, 1927. Serial No. 189,008.

This invention may be employed with particular advantage in the manufacture of what is known as carbon paper, to wit, thin tissue paper coated with transfer material; 5 for it is highly important to have the paper pass into the coating machine substantially uniformly and straight; to avoid waste of the material at its edges and to facilitate the operation of coating it. The manufacturers of such paper furnish the same to the trade in large rolls from which the paper is unwound into the carbon coating machines. 10 Although such paper is intended to be plane, it is not uniformly so and tends to shift 15 from side to side in its passage to the coating machine, in accordance with the departure of the paper from the ideal plane toward either edge of it, i. e., if the paper is buckled on the right hand edge, it tends 20 to shift toward the left, and vice versa.

In order to correct such tendency for the paper to run crookedly into the coating machine from its original supply roll it is necessary to angularly shift the axis of 25 rotation of such roll from time to time, out of parallel relation with the axis of the first roller over which the paper passes in the coating machine; and my present invention provides means for readily effecting 30 such adjustment without interfering with the continued operation of the machine.

My invention includes the various novel features of construction and arrangement hereinafter more definitely specified.

35 In said drawings; Fig. I is a fragmentary elevation of the initial end of a carbon paper coating machine embodying my invention.

Fig. II is a fragmentary plan view of 40 the mechanism shown in Fig. I.

In said figures the machine is provided with parallel side frames 1 in which are journaled the shafts 3 and 4 of a pair of feed rollers 5 and 6. Said roller 5 is arranged to be positively rotated in the direction of the arrow marked thereon and said roller 6, which is free to gravitate toward said roller 5, so as to pinch the paper web 7 between them, is provided with a 45 cloth cover 8 to frictionally engage the paper and is idly rotated by such frictional engagement. The paper is thus fed in the direction indicated by the arrows and is drawn from the supply roll 10 over the guide roller 11 which latter has its shaft 12 journaled 55 in said frames, and is the initial roller encountered by the paper 7 in its introduction to the coating machine from the supply roll.

Said supply roll 10, in the form furnished 60 by the manufacturer, is adapted to be rigidly connected with the shaft 14, conveniently by conical wedge sleeves 15 which are driven into the opposite ends of the roll in substantially tight relation with said shaft 14. 65 If the paper 7 were perfectly plane, it would suffice to mount said shaft 14 with its axis parallel with the shaft of said initial roller 11. However, in order to effect the angular adjustment of the axis of said shaft 14 with 70 reference to the stationary axis of said initial roller 11, I provide the pair of slide journal boxes 17 each having a bight flange 18 adapted to be looped over a stationary abutment 20 upon the respective side frame 75 1. The stress of the feed rollers 5 and 6 upon the paper 7 tends to pull the roll 10, and said boxes 17, toward the right in the drawings, and such movement is opposed by the journal screws 21 which are in screw 80 threaded engagement with the respective bight flanges 18 and which are adjustable by their wheel heads 22 to bear upon the respective abutments and thus determine the position of the axis of the shaft 14, which 85 is coincident with that of the roll 10 of paper 7. Said journal screws 21 are thus carried, independently of the frame 1, by their respective bearings 17, in which they are axially adjustable by rotation, and each 90 of said bearings 17 is at all times loose and removable with respect to said frame 1, without disturbing the adjustment of its screw 21. It is to be understood that by advancing and retracting the respective screws 95 21, the axis of the shaft 14 may be made parallel with the axis of the initial roller 11 of the coating machine, or be angularly diverged with respect thereto toward either side of the machine in compensation for 100 every departure of the paper web 7 from the ideal plane. As before noted, said bearings 17 are loose upon the frame 1 upon which they are retained by the abutments

20 projecting in their bight flanges 18; so that such adjustments do not cause the shafts 14 to bind in said bearings, which adjust themselves to the changed angular relation 5 of the shaft axis consequent upon any differential adjustment of said screws 21. For instance, if the paper 7 is found to be departing from its proper position toward the left in its movement toward the initial roller 10 11, because it is buckled upon its right hand edge, i. e., is longer upon its right hand edge than upon its left hand edge, such movement may be checked and the paper caused to run straight by positioning the axis of the shaft 15 14 so that it is more remote from the axis of the shaft 11 at the right hand side than at the left hand side of the machine and such adjustment may be effected by turning the right hand screw 21 to the right while 20 bearing against its abutment 20 and thus reTRACTING the slide bearing 17. If and when the paper runs straight following such adjustment, the rotation of said screw 21 may be reversed to restore the axis of the shaft 25 14 to parallel relation with the initial roller 11. Similar adjustment of the other journal screw 21 may be effected to correct buckling upon the left hand edge of the paper web 7 which tends to divert it toward the right 30 with reference to the initial roller 11.

Although said shaft 14 may be directly journaled in the journal boxes 17, if it is desired to merely straighten and not stretch the paper 7 by adjustment of the screws 21 35 I prefer to mount it upon removable shaft bearing blocks 24 in the respective seats 25 of said journal boxes and to oppose such bearing blocks with respective brake shoes 26 which may be frictionally engaged with 40 the shaft 14 by respective adjustable brake screws 28 which may be manipulated by their wheel heads 29, in order to effect the cooperative straightening and stretching of the paper web 7 above contemplated.

45 It is to be understood that said brake screws 28 may be adjusted to predetermine the tension upon the paper web 7 required to revolve the shaft 14 of the roll 10 when thus clamped by the brake shoes 26 and such 50 frictional engagement must, of course, be varied in accordance with the thickness and condition of the paper being unrolled; being, of course, least for the thinnest and most fragile paper.

55 Therefore, my invention includes means, coordinately and cooperatively adjustable by said screws 21 and 28, to both straighten and stretch the web 7 between said feed rollers 5, 6 and said shaft 14. That is to say, said screws 21 and 28 must be coordinately and cooperatively adjusted to produce upon the web 7, the effect which it is the object of my invention to attain.

However, I do not desire to limit myself 60 to the precise details of construction and ar-

rangement herein set forth, as it is obvious that various modifications may be made therein without departing from the essential features of my invention, as defined in the appended claims.

70

I claim:

1. A device adapted for angularly adjusting a shaft; comprising a slide journal box having a bight flange adapted to be loosely, 75 removably looped over a stationary abutment; a journal screw extending in threaded engagement with the end of said bight flange, axially movable by rotation therein, and adapted to bear upon such abutment, whereby rotation of said screw is adapted to shift said journal box relatively to said abutment, in but one direction, and said screw may be rotated in the opposite direction without relative movement of said box and abutment.

2. In a device adapted for angularly adjusting a shaft arranged to carry a roll of buckled web; the combination with a frame comprising opposite side members; of a roller; bearings holding the axis of said roller in fixed transverse relation to said frame members; an abutment on each of said frame members; a pair of slide journal boxes, oppositely mounted on said frame members and having respective bight 95 flanges, respectively loosely, removably looped over said abutments; a pair of shaft bearing blocks, coaxially alined in the respective boxes; a web roll shaft journaled in said blocks; and means, including screws 100 respectively in threaded engagement with said boxes and axially movable therein, by rotation thereof, in opposition to said abutments and adjustable to variably set said boxes with respect to said abutments; whereby said boxes are adjustably movable to angularly shift said shaft, to and from parallel relation with said roller, and thereby compensate for buckled condition of either edge of the web carried by said shaft, 105 and thus straighten said web between said roller and said shaft.

3. In a device adapted for coordinately angularly adjusting a shaft arranged to carry a roll of buckled web, and controlling the revolution of said shaft; the combination with a frame comprising opposite side members; of a pair of feed rollers arranged to progress such web between them; bearings holding the axes of said feed rollers at right 115 angles to said frame members; an abutment on each of said frame members; a pair of slide journal boxes, oppositely mounted on said frame members; a pair of shaft bearing blocks, coaxially alined in the respective boxes; a web roll shaft journaled in said blocks; a pair of brake shoes, respectively fitted over said shaft, in said boxes; means in said boxes, arranged to clamp said shoes upon said shaft and thereby friction- 120 125

- ally oppose the rotation of said shaft; and journal screws, adjustable to variably set said boxes with respect to said abutments; whereby said boxes are adjustably movable 5 to angularly shift said shaft, to and from parallel relation with said feed rollers, and thereby compensate for buckled condition of either edge of the web carried by said shaft, and thus cooperatively straighten 10 and stretch said web between said feed rollers and said shaft.
4. In a device adapted for coordinately angularly adjusting a shaft arranged to carry a roll of buckled web, and controlling 15 the revolution of said shaft; the combination with a frame comprising opposite side members; of a pair of feed rollers arranged to progress such web between them; bearings holding the axes of said feed rollers at 20 right angles to said frame members; and abutment on each of said frame members; a pair of slide journal boxes, oppositely mounted on said frame members and having respective bight flanges, respectively looped over said abutments; a pair of shaft bearing blocks, coaxially alined in the respective boxes; a web roll shaft journaled in said blocks; a pair of brake shoes, respectively fitted over said shaft, in said boxes; respective adjustable brake screws, in said boxes, arranged to clamp said shoes upon said shaft and thereby frictionally oppose the rotation of 25 said shaft; and adjustable journal screws, respectively extending in the bights of said flanges, against said abutments; whereby said boxes are adjustably movable to angularly shift said shaft, to and from parallel relation with said feed rollers, and thereby 30 compensate for buckled condition of either edge of the web carried by said shaft, and thus cooperatively straighten and stretch said web between said feed rollers and said shaft.
- 35
5. In a device for coordinately angularly adjusting a shaft arranged to carry a roll of buckled web, and controlling the revolution of said shaft; the combination with a frame comprising opposite side members; of a pair of feed rollers arranged to progress such web between them; bearings holding the axes of said feed rollers at right angles to said frame members; an abutment on each of said frame members, alined parallel with said roller axes; a pair of slide journal boxes, oppositely mounted on said frame members and having respective bight flanges, respectively looped over said abutments; a pair of shaft bearing blocks, coaxially alined in the respective boxes; a web roll shaft journaled in said blocks; a pair of brake shoes, respectively fitted over said shaft, in said boxes; respective adjustable brake screws, in said boxes, arranged to clamp said shoes upon said shaft and thereby frictionally oppose the rotation of said shaft; and adjustable journal screws, respectively extending in the bights of said flanges, against said abutments; whereby said boxes are adjustably movable to angularly shift said shaft, to and from parallel relation with said feed rollers, and thereby 40 compensate for buckled condition of either edge of the web carried by said shaft, and thus cooperatively straighten and stretch said web between said feed rollers and said shaft.
